UNITED STATES PATENT OFFICE.

WILLIAM B. ROMIG, OF BETHLEHEM, PENNSYLVANIA, ASSIGNOR TO LEHIGH MANUFACTURING COMPANY, OF SAME PLACE.

SCOOP.

SPECIFICATION forming part of Letters Patent No. 239,116, dated March 22, 1881.

Application filed February 18, 1881. (No model.)

To all whom it may concern:

Be it known that I, WILLIAM B. ROMIG, a citizen of the United States, residing at Bethlehem, in the county of Northampton and State of Pennsylvania, have invented a new and useful Improvement in Constructing Scoop-Shovels, of which the following is a specification.

My improvement relates to a class of shovels known to the trade as "scoops."

Heretofore in the manufacture of scoop-shovels the sheet of metal is trimmed to the required size and form. A V-shaped piece is then cut out at a point corresponding to the attachment of the straps, and the blank is then pressed or swaged between dies, which brings the bowl to the required shape; but the edges of the V-shaped notch are not brought together. The straps are then riveted to the bowl, in order to properly brace the blade. The points of the straps must extend below the V-notch and curve of the blade. This brings the rivet and points in the line of wear, so that when the rivet which secures the points of the straps wears out or gives way the point of the back strap is liable to curl up or break off, loosen the straps, rendering the scoop useless before the bowl is but little worn.

To overcome the above I have invented a new and improved manner of constructing scoop-shovels, which consists, first, in cutting the V-shaped notch so that when the bowl is formed to shape the edges of the V-notch will lap sufficient to weld together, which I do over or under a proper-shaped former or dies, and (at the same heat, if desired) I weld to the bowl a piece of iron, from which is formed the back strap; second, riveting the inside strap to a scoop-bowl, as above constructed, so as to bring the rivets above the line of wear, all as will be hereinafter described, referring to the accompanying drawings, making a part of this specification, in which—

Figure 1 is a view of a scoop-blank. Fig. 2 is a view of a scoop stamped and welded according to my invention. Fig. 3 is a view of the same with the inside strap riveted to the bowl. Fig. 4 is a view of the blank formed ready for welding. Fig. 5 is a view of the inside strap. Fig. 6 is a sectional view of the bowl and straps.

Similar letters refer to similar parts throughout the several views.

Fig. 1 represents a scoop-blank cut from a sheet of steel, spring or cast. This blank is 55 heated and pressed between formers or dies, which gives it the form shown in Fig. 4, with the edges of the V-notch lapped, as shown by the full and dotted lines. The bowl is then heated at the lap to a welding-heat, when the 60 lap is welded over a proper tool or former. At the same time a piece of wrought-iron is welded to it for the back strap, A, which, after being trimmed, will form a scoop with one strap, as shown in Fig. 2. The dotted lines show the 65 line of the welds.

B is the inside or front strap. This strap is made of wrought-iron, and formed by suitable dies, and punched for rivets, as shown in Fig. 5. Holes for the rivets are punched into the 70 bowl and back strap to correspond with the holes in the front strap, as shown in Figs. 2 and 5. The hole for the rivet that fastens the point of the strap B is above the line of wear, as shown in section, Fig. 6. This brings the 75 rivet-heads all above the line of wear, making a scoop with a steel bowl, smooth back, all rivets above the line of wear, and wrought-iron straps for the handle.

I am aware that it is not new to weld a 80 wrought-iron strap to a steel blade of a shovel. This I do not claim; but

I claim—

1. A scoop-shovel bowl formed by notching, lapping, and welding, as shown, described, and 85 for the purpose specified.
2. In combination with a scoop-shovel bowl constructed as above described, the wrought-iron back strap welded to the bowl, as shown and described.
3. In combination with a scoop-shovel bowl and back strap constructed as before described, the inside or front strap, B, riveted to the bowl with rivets, all above the line of wear, as shown, described, and for the purpose specified.
